UNITED STATES PATENT OFFICE.

WILLIAM H. MARKLAND, OF BROOKLYN, NEW YORK, ASSIGNOR TO TUCKER
& BAXTER, OF SAME PLACE.

DOOR-CATCH ADAPTED TO BE OPERATED BY ELECTRICITY.

SPECIFICATION forming part of Letters Patent No. 350,312, dated October 5, 1886.

Application filed February 9, 1886. Serial No. 191,276. (No model.)

To all whom it may concern:

Be it known that I, WILLIAM H. MARKLAND, a citizen of the United States, residing in the city of Brooklyn, county of Kings, and 5 State of New York, have invented certain new and useful Improvements in Door-Catches Adapted to be Operated by Electricity; and I do hereby declare that the following is a full, clear, and exact description of the invention, 10 reference being had to the accompanying drawings, which form a part of this specification.

The object of this invention is a door-catch especially adapted to hold heavy doors in position open and to release the same by the action of electricity; and it consists of a spring-bolt of peculiar construction provided with a stop to hold it in position against a trigger, and 15 of a releasing device whereby the stop is freed 20 and the spring of the bolt allowed to operate upon it to release the door.

In the drawings, Figure 1 is an elevation of my invention. Fig. 2 is a side view of the same. Fig. 3 is a plan of the same. Fig. 4 shows the same as applied to a sliding door. Fig. 5 is an elevation of my invention, showing 25 a modified arrangement of the bolt. Fig. 6 is an end view of Fig. 5. Fig. 7 is a side view of a modification of the releasing device. Fig. 8 is 30 a plan view of the releasing device, Fig. 7.

Similar figures of reference indicate like parts in all the drawings.

A is a suitable plate on which the parts may be mounted; B, the magnets, with wires carried to binding-posts *a a*, and then suitably connected by wires *a' a'* to the battery C and thermostat D, as shown in Fig. 4.

Beneath the magnets B, in suitable bearings, 40 is pivotally mounted an armature-lever, *b*, which carries the armature *c*, and to the outer end of the lever *b* a rod, *d*, is pivotally connected, which is weighted by a suitable weight, *d'*. At the outer end of the lever *b* a tension-spring, *e*, is attached, which is regulated by an 45 adjustment-screw, *e'*, in the post E. Below the lever *b* a trigger, *f*, is pivoted to the plate A, the outer end of which is supported by the set-screw F, by which its downward movement 50 may be adjusted. The rod *d* is secured to this trigger *f* by means of a pin or screw, *g'*, on the

trigger *f*, which screw plays freely in the vertical slot *g* of the rod *d* until it engages with the lower part of the slot by the upward movement of the rod *d*. By means of the tension-spring *e* the weighted rod *d* is adjusted so that 55 the parts will be supported on the screw F, but will be nearly balanced, in order that but little electrical energy may be required to draw up the armature *c*, and with it the rod *d* and trigger *f*. By this arrangement the armature 60 is attracted and approaches the magnet, meeting at first with but little resistance from below, and as its motion is accelerated and the attracting power of the magnet increases by the nearer position of the armature, the impetus thereby given to the parts will act upon the trigger by percussion, when the lower edge of the slot *g* strikes against the pin *g'*, and not by a gradual drawing motion, by which operation 65 the power exerted by the releasing device is proportionately very great.

I show two methods of arranging the bolts for use in my invention, one, as shown in Figs. 1, 2, and 3, in which the spring-bolt G may be flat. This bolt is arranged to move in 75 a cage formed on the plate A by the strip I, supported on suitable standards, J. In this frame friction-wheels *l l* are arranged, which support and guide the bolt G above and below. To support and guide the bolt on its 80 sides, I provide two friction-wheels fixed in position and two that move with the bolt G. At the side of the bolt nearest the door H the fixed friction-wheel *m* is on the side of the bolt against which the door impinges, and on the 85 other end the fixed friction-wheel *m'* is on the opposite side of the bolt. The movable friction-wheels *n n'* form a carriage, being supported by the strips *i i*, which pass diagonally across the bolt, between it and the spring *k*, and this 90 carriage, consisting of the strips *i i* and friction-wheels *n n'*, is free to move with the bolt G forward and backward, the forward wheel, *n*, being confined in the L-piece *o o'*. By this arrangement the friction of moving the bolt G 95 is reduced to a minimum.

Near the middle of the bolt G a stop, *p*, is attached thereto, between which and the L-piece *o o'* a spring, *k*, is inclosed around the bolt, which serves to throw the bolt inward and 100

away from the door H, when free to act. The door H may also be provided with a friction-roller, h, against which the bolt G operates. On the L-piece o² rubber or other suitable elastic buffers, j j, may be provided, to receive the impact of the stop p when the bolt G is thrown back.

The method of operation is as follows: The door H is run back from its opening M on the incline L, which is suitably secured to the wall K. The bolt G is then pushed forward until it obstructs the door, as shown clearly in Fig. 3, the trigger f being raised to let the stop p pass under it, and then the trigger f is lowered until it rests against the stop p, preventing the bolt G being pushed back by the action of the spring k and retaining it in position against the door. When the thermostat D is heated to the designated degree of temperature, the circuit is closed, exciting the magnet B and attracting the armature c. As the armature approaches the magnet its motion is accelerated and the attracting-power of the magnet increased, so that when the end of the slot g strikes the pin g' on the trigger f the blow is of considerable power, disengaging the trigger f from the stop p, allowing the spring k to operate, throwing back the bolt G from the door H, which, being released, runs down the incline L and closes its opening. This arrangement of bolt and bearings is especially applicable where very heavy doors are employed, as a spring, k, of considerable resistance may be operated by a comparatively feeble magnet by means of the percussive operation of the releasing parts.

For lighter doors I may employ the bolt and bearings shown in Figs. 5 and 6. In this the angled supports q q are secured to the plate A. Within each are arranged two concave friction-rollers, r r, between which the bolt G' is supported. The bolt G' has secured to it a suitable stop, p', which may be in the form of a disk, and between this stop and the bearing q nearest the door the spring k is enclosed. The trigger f operates against the stop p' to hold the bolt in place. The operation of the other parts is the same as has already been above described.

In Figs. 7 and 8 is shown a modification of the releasing device. In this the stop p' of Fig. 5 is held in position by the end of the rod d², the trigger f being dispensed with. In this arrangement of my invention a support, R, is attached to the plate A, which carries two friction-wheels, s s, between which the rod d² is supported at an incline to the plate A. On the other side of the rod d² a friction-wheel, t, is mounted in the support P, and this wheel t bears the pressure of the stop p' upon

the rod d². The armature-lever b² is weighted, and is balanced in position by the spring e, as in the other instance of my invention. The rod d² is attached to the lever b² by means of the slot and screw u, so that they will not engage until after the armature has traversed a portion of its path toward the magnet. To adjust the downward movement of the rod d², a sliding stop, r', is attached thereto, the lower end of which rests upon the support R when fixed in suitable position. As the magnet B becomes excited, it attracts the armature c, bringing up the lever b² until the slot and screw come into engagement, whereby the rod d² is struck upward, releasing the stop p', allowing the spring k to throw back the bolt G'. 65 70 75

By this invention a very effective and reliable door-catch is operated with but little expense of battery, and all of the parts are simple and not liable to get out of order. 80

Having thus described my invention, what I claim as new, and desire to secure by Letters Patent, is—

1. In a door-catch adapted to be released electrically by percussion, a spring-bolt, G, 85 provided with stop p, trigger f, rod d, and armature c, in combination with a suitable magnet and battery adapted to actuate the armature, substantially as described and shown.

2. In a door-catch adapted to be released 90 electrically by percussion, a suitable support, as A, angled portions q q, and friction-rollers r r, in combination with a spring-bolt, G', provided with the stop p' and trigger f, substantially as described and shown. 95

3. In a door-catch adapted to be operated 100 electrically by percussion, a spring-bolt, G, strips i i, and friction-wheels n n', in combination with the friction-wheels l l and m m', arranged substantially as described and shown. 105

4. The percussive releasing device described, consisting of a bolt with a stop, as p', and a suitable magnet, in combination with an armature, c, carrying a rod, as d', adjusted relative to the stop p' to operate upon the same 105 after the armature has traversed a part of its path toward the magnet, substantially as described and shown.

5. A door-catch consisting of a spring-bolt, G, provided with stop p, trigger f, rod d, and 110 armature c, in combination with a magnet, B, a suitable battery and its connections, and a thermostat interposed in the circuit and adapted to close the circuit and actuate the armature at a determined degree of temperature, substantially as described and shown. 115
